UNITED STATES PATENT OFFICE.

CHARLES S. BATDORF, OF BROOKLYN, NEW YORK.

COMPUTING-PRICE-SALES DEVICE.

Application filed December 19, 1923. Serial No. 681,465.

To all whom it may concern:

Be it known that I, CHARLES S. BATDORF, a citizen of the United States, and a resident of Brooklyn, in the county of Kings and 5 State of New York, have invented certain new and useful Improvements in Computing-Price-Sales Devices, of which the following is a specification.

The object of the invention is to provide 10 a portable manually operative device to be carried by a salesman at a gas station, for illustration, for computing the total price or charge for a quantity of gasoline sold and impressing the same, with other data, 15 on an original check or sales slip from which a transfer is at the same time made to a duplicate check or sales slip to be handed to the customer, while the original check or slip is retained for the owner of the station.

20 In carrying out my invention I make use of a rotary sleeve on which I key several impression wheels to denote respectively the number of gallons of gasoline sold and the total price charged therefor and on 25 which sleeve is secured an operating knob by which the sleeve and wheels thereon are rotated to the proper extent and which bears numbers, from "1" to "20" inclusive, indicating gallons, to guide the operator in setting the impression wheels. I also equip the 30 body of the device with a stationary impression plate which may bear standard indications, as in the present instance, "Gallons of gas," a letter or character denoting the salesman, as "A," and a dollar mark, as 35 "¢." The device is equipped with a platen on which the sales slips or checks are placed and by which said slips or checks are pressed against the impression wheels and plate to 40 receive imprints therefrom.

The invention will be fully understood from the detailed description hereinafter presented, reference being had to the accompanying drawings, in which:

45 Fig. 1 is a central vertical longitudinal section through a price computing sales device embodying my invention;

Fig. 2 is a top view of the same;

50 Fig. 3 is a vertical transverse section through the same, taken on the dotted line 3—3 of Fig. 1;

Fig. 4 is a similar section through the same taken on the dotted line 4—4 of Fig. 1;

Fig. 5 is a horizontal section through the same taken on the dotted line 5—5 of Fig. 4; 55

Fig. 6 is a perspective view of the duplicating sales book employed in connection with the device of my invention;

Fig. 7 is a detached face view of an original check printed on my device, said check 60 having a carbon back and to be retained by the salesman for his house, while the duplicate check is shown in Fig. 6 and is to be detached and handed to the customer; Fig. 4 indicates the manner of employing the sales 65 book in connection with my device in order to produce the checks shown in Figs. 6 and 7;

Fig. 8 is a view corresponding with Fig. 1 illustrating a modified construction embodying my invention, Fig. 8 being a section 70 taken on the dotted line 8—8 of Fig. 10;

Fig. 9 is a front end view of the same, taken from the left hand end of Fig. 8;

Fig. 10 is a vertical section through the 75 same taken on the dotted line 10—10 of Fig. 8;

Fig. 11 is a longitudinal section through the same taken on the dotted line 11—11 of Fig. 8; 80

Fig. 12 is an elevation showing in flat diagrams or strips the numbering on the several rotary wheel members of my device, Fig. 12 being applicable alike to the construction shown in Figs. 1 to 5 inclusive and 85 that presented in Figs. 8 to 11 inclusive, and

Fig. 13 is a perspective view of a sales 90 slip adapted for use on the device in the manner indicated in Fig. 10.

In the drawings, referring to Figs. 1 to 5 inclusive, 20 designates the general body 95 of the device and 21 a pivoted platen which is movable toward the body 20 and normally is held pressed therefrom by means of a

spring 22 flexed between the handle 23 on 95 said platen and a stationary handle 24 rigid with the end-piece 25 of the body 20. The platen 21 and handle 23 may be cast in one piece, and this piece is pivotally mounted on a pin 26 supported from the end-piece 25. 100 The handle 24 may be cast with the end-piece 25, and said handle will preferably have a hole 27 as means for suspending the device from a hook or the like.

The body 20 is composed of the end-piece 105 25, an elongated shell 28 which is in the

nature of a hood and secured by screws to said end-piece and a base-plate 29 to which the lower edges of said shell are secured by screws, as shown in Fig. 5. The base-plate 29 is shorter than the shell 28, thereby leaving a space 30 at the rear end of said plate and a space 31 at the front end of said plate (Fig. 5). In the space 30 are mounted the ink-pad rollers 32, the shafts of said rollers being set into bearing recesses in the facing portions of the plate 29 and end-piece 25, and in the space 31 are provided the ink-pad rollers 33, whose shafts are mounted at their rear ends in the front end of the base-plate 29 and at their front ends in the in-turned flange 34 formed on the front end of the shell or housing 28.

In its lower surface the base-plate 29 is formed with a longitudinal dove-tail recess 35 into which is slid a type or impression plate 36 having, in relief, type or impression characters 37.

Within the housing 28 is secured a longitudinal axle 38 which extends from the end-piece 25 forwardly through the open forward end of said housing, the rear end of said axle being secured to said end-piece by a threaded stem 39 and nut 40.

Upon the axle 38 is rotatably mounted a sleeve 41, and upon this sleeve is keyed to rotate therewith, a rear impression wheel 42 having type or impression characters 43, a forward impression wheel 44 having type or impression characters 45 and an operating knob 46 having an annular finger-piece or flange 47 and a conical body 48 bearing on its surface a series of numerals ranging consecutively from "1" to "20" inclusive, as shown by the diagram strip 48 in Fig. 12, and denoting, in this instance, gallons of gasoline to be sold, as called for. The wheel 44 is formed on its forward end with a hub 49 upon which is keyed a ring or wheel 50 bearing type or impression characters 51, shown on the diagram of said ring or wheel in Fig. 12 at 50. The wheel 44, at its hub portion 49, and the ring or wheel 50, are engaged by the inner end of the knob 46, as shown in Fig. 1, and the knob is held on the sleeve 41 by being keyed thereto and also by means of the screw 52 whose stem enters the forward end of the axle 38 and whose head overlaps the central portion of said knob.

The wheel 42 rotates, at its lower portion, within the space 30 at the rear end of the base plate 29 and against the ink-rollers 32, and the wheels 44, 50 rotate, at their lower portions, within the space 31 at the forward end of the base-plate 29 and against the ink-rollers 33.

The knob 46 is exposed at the forward end of the shell or housing 28, and the wheels 42, 44 and 50 are concealed within said shell or housing. I preferably mount

in the end-piece 25 a pointed spring-pawl 53 to snap into indentations in the rear face of the wheel 42, as shown in Fig. 1, these indentations being aligned with the impression characters on the wheel and the pawl serving to exert pressure against the wheel and steady it in its printing positions.

The type or impression characters on the wheel 42 are represented on the diagram 42 in Fig. 12, and they are used to imprint on the sales slips the number of gallons of gasoline, at each sale, actually ordered and sold, the number "10" on the slips shown in Figs. 6 and 7 having been made by the wheel 42 and indicating that ten gallons of gasoline had been sold to a customer.

The type or impression characters on the wheels 44, 50 are represented at 44, 50 in Fig. 12, and they are used to imprint on the sales slips the total charge for the gasoline sold at each sale thereof, the figures "2.00 5" in Figs. 6 and 7 representing a sale of ten gallons of gasoline at 20½ cents a gallon, the figures "2.00 5" indicating two dollars and five cents. The type or impression characters on the wheel 44 indicate dollars and cents, and they commence at the middle of the strip 44 shown in Fig. 12 or at the bottom central point on the wheel 44, with the number "20," indicating 20¢, and at a corresponding point on the wheel 42 is the numeral "1," indicating one gallon on the wheel 42 and the price thereof 20¢ being indicated on the wheel 44. At a corresponding point on the wheel 50 is the character ½ which represents a fraction of a cent. If the wheels 42, 44, 50 are read across on the line of the said numeral "1," the number "20" and the indication "½," it will be seen that the imprint on the sales slip will read 1 gallon of gasoline, 20½ cents. On the wheel 42 I commence with the numeral "1" at a central point of the wheel, and thence the numerals on the wheel continue consecutively to "20" inclusive. On the wheel 44, which is a total price wheel, it will be seen that I commence at a point thereon aligning with the numeral "1" of wheel 42, with the number 20, indicating 20¢, and that from that point the amounts on the wheel 44 are multiples of 20 and follow in succession around the wheel up to the figures "4.00," the latter representing \$4.00 and indicating what would be printed on the sales slip if twenty gallons of gasoline has been sold at twenty cents a gallon. On the wheel 50, I commence with the character "½" on line with the "1" on wheel 42 and the number "20" on wheel 44, as may be observed in Fig. 12, and thence the characters on the wheel 50 increase by one-half cent fractions around the wheel to the final number "10," which denotes ten cents. If a sale is made of twenty gallons of gasoline at 20½¢ a gallon, the imprint on the sales slip will

be "4.00 10," denoting \$4.10, the "ten" having been imprinted from the wheel 50 and the "4.00" from the wheel 44. The wheel 50 will only be used when gasoline is sold

5 at a price involving the fraction of a cent.

The numerals on the knob 46 commence with "1" at the top of the knob and continue along around the knob consecutively to the numeral "20." The numeral "1" on the knob 10 46 is normally at the top of the knob, and the numeral "1" on the wheel 42 and the amount "20" on the wheel 44 and the fraction "1/2" on the wheel 50 will always be at the bottom of the wheels 42, 44, 50 at 15 the same time that the numeral "1" on the knob 46 is exposed at the upper side or top thereof.

On a sale of ten gallons of gasoline the knob 46 will be turned until the number 20 thereon appears at the top in line with the index 80 on the shell 28 (Fig. 2), and this turning motion of the knob will be communicated through the sleeve 41 to the wheels 42, 44, and from the wheel 44 to 25 the ring or wheel 50, and under this turning motion of the knob 46 to expose at its top the numeral 10, the wheels 42, 44, 50 will turn until at the bottom thereof will appear the number 10 on the wheel 42, "2.00" 30 on the wheel 44, and "2" on the wheel 50, so that thereafter when an impression is made on the sales slip the slip will show the number "10" from the wheel 42, the numerals "2.00" from the wheel 44, and 35 the numeral "5" from the wheel 50, showing a total sale of ten gallons of gasoline at 20½¢ a gallon or 2.00 5. The dollar sign (\$) will finally appear on the check shown in Fig. 6, and the checks will be numbered 40 in regular series, the original check shown in Fig. 7 and the duplicate shown in Fig. 6 bearing corresponding numbers, as "1." The duplicate sales slip will also, as presently explained, receive an indication of the 45 salesman, as the letter "A," the "A" denoting who it was that made the sale.

The wheels 42, 44, 50 by reason of their engaging the ink-rollers 32, 33, will make ink impressions on the original check, as 50 shown in Fig. 7, and these will be transferred to the duplicate check from the carbon back on the original check. In this instance also the following will be transferred to the duplicate check, to-wit: "Gallons of 55 gas A \$," in addition to the numeral "10" and the price "2.00 5," the transfer of the words "Gallons of gas A" and the "\$" being made by the type characters 37 on the plate 36 secured in the bottom of the base member 29.

The sales-slips will preferably be in pad form, as indicated in Fig. 6, and the top check or slip of the pad is that shown in Fig. 7, and it has a carbon back so as to transfer to the duplicate check or slip shown

in Fig. 6. After a sale has been consummated the duplicate check or sales-slip shown in Fig. 6 is detached and handed to the customer.

The means for enabling the wheels 42, 44, 50 and plate 36 to make their impressions on the sales-slip consists of the pivoted platen 21 having the yielding rubber or other pad 60 on its upper face. Two of the slips from the pad shown in Fig. 6, one being an original and the other the duplicate, are inserted between the platen 21 and the body of the device, and after the slips have been positioned the handle 23 is squeezed toward the handle 24, and this causes the platen 21 to press the slips against the wheels 42, 44, 50 and plate 36 and thereby said wheels and plate are enabled to make their impressions on the original slip and by the carbon transfer, onto the duplicate sales slip. In Fig. 4 I illustrate two of the companion sales slips as having been introduced between the platen 21 and the body of the device.

From the foregoing description it will be understood that the wheels 42, 44, 50 are set to make their impressions by the manual rotation of the knob 46 and sleeve 41. The knob 46 is rotated to the extent of the number of gallons called for by a purchaser, from 1 to 20 inclusive. Whatever numeral on the knob 46 may be turned to the upper side of said knob, at the index 80, will result in a corresponding numeral on the wheel 42 being turned to the lower side of said wheel, and also in the wheels 44, 50 being so turned that the appropriate characters thereon, according to the numeral at the lower side of the wheel 42, will appear in impression position at the bottoms of said wheels. The numbers on the wheels and on the knob 46 are oppositely disposed so that when the numeral 1 is at the top of the knob 46 the numeral 1 is at the bottom of said wheel, and this system is carried out through all of the wheels. The plate 36 in the bottom of the base 29 carries permanent characters, and these characters will vary with the desire of the owner of the device. The characters 37 on the plate 36 may be of sharp character so as to leave their imprint on the original check shown in Fig. 7 while transferring through the carbon on the back of said check the like characters to the duplicate check or slip shown in Fig. 6.

The device of my invention will be used by salesmen selling gasoline at the customary gas stations or elsewhere, and its purpose is to compel fairness in the sales transactions and protect both the customer and the owner of the station. With the use of my device a sales transaction is recorded in duplicate on the two slips, one of which is retained in the pad for the owner of the station and the other is handed to the customer and apprises him of the number of

80

85

125

130

gallons of gasoline delivered to him and the total price therefor.

In Figs. 8 to 11 inclusive I illustrate a modification of the invention without departing from the principle of operation or the details connected with the impression wheels. In Fig. 8 the body or casing of the device is a cylindrical casting 70 having a thumb or finger loop 71 at its upper side and a hinged platen 72 at its lower side, said platen being secured by a pivot 73 and having a thumb or finger hole 74. The construction shown in Fig. 8 contains the same operative elements shown in Fig. 1, and they will be correspondingly numbered in Fig. 8 so as to avoid repetition, these features being the stationary axle 38, rotary sleeve 41, impression wheel 42, impression wheel 44, ring or wheel 50, knob 46, screw 52 and impression plate 36. These features just enumerated are the same in construction and operation as the like features already described with respect to Figs. 1 to 5 inclusive. In the construction shown in Fig. 8 no ink rollers such as 32, 33 are made use of, the object being to so firmly press the sales slips between the platen 72 and the impression characters carried by the wheels and plate 36, that on the original check numbered 75 in Fig. 13 said characters may appear by imprint, while at the same time the carbon on the back of the check 75 will transfer the characters to the duplicate check 76. The duplicate check will be handed to the customer and the check 75 retained for the owner of the station. In both forms of my invention the wheels 42, 44, 50 are detachable and renewable, and particularly the wheels 44, 50 may be removed, after the knob 46 has been withdrawn so that new wheels 44, 50 may be applied to the device on changes in price of gasoline. When gasoline is sold at a price which does not include the fraction of a cent on a gallon, the ring or wheel 50 will be taken off and hence not used at all. When the price of gasoline varies from the standard figures found on the wheel 44, this wheel will be removed and be replaced by a wheel having the correct total amounts featured thereon.

I have described my invention as employed in the sale of gasoline at "Gas stations," but obviously the device may be employed in the sale of oil and many other commodities or merchandise, and I do not therefore limit the invention to use in the sale of gasoline, although I recognize the necessity of employing the device at "Gas stations" and the same was especially designed for such use.

I do not limit the invention to all the details of form and construction described in illustrating the preferred embodiment of the invention, since I am aware that these details may be modified without departure

from my invention as defined in the appended claims.

What I claim as my invention and desire to secure by Letters Patent, is—

1. A manually operative computing sales device, comprising a body portion and a platen between which sales slips may be pressed to receive thereon the record of a sale, said body portion comprising an elongated casing having a rigid back portion and being open at its outer or forward end and having a rotary shaft provided on one end with an exposed operating knob bearing numerals indicative of the quantities of merchandise sold, said shaft being insertable and removable through the open outer end of said casing and said knob being keyed on the outer end of said shaft and removable therefrom, an impression wheel mounted on said shaft and having thereon in relief a series of numerals corresponding with the numerals on said knob and also indicative of the quantities of the merchandise sold, and an impression wheel mounted on said shaft and bearing in relief impression characters denoting the total price to be charged for the units represented by the corresponding numerals on said knob and said quantity impression wheel, said impression wheels being adapted to make a record on the sales slips pressed against them of the quantity of merchandise sold and the total charge therefor, and said impression wheels being keyed on said shaft and slideable to position thereon and therefrom.

2. A manually operative computing sales device, comprising a body portion and a platen between which sales slips may be pressed to receive thereon the record of a sale, said body portion comprising an elongated casing having a rigid back portion and being open at its outer or forward end and having a rotary shaft provided on one end with an exposed operating knob bearing numerals indicative of the quantities of merchandise sold, said shaft being insertable and removable through the open outer end of said casing and said knob being keyed on the outer end of said shaft and removable therefrom, an impression wheel mounted on said shaft and having thereon in relief a series of numerals corresponding with the numerals on said knob and also indicative of the quantities of the merchandise sold, an impression wheel mounted on said shaft and bearing in relief impression characters denoting the total price to be charged for the units represented by the corresponding numerals on said knob and said quantity impression wheel, and a stationary plate mounted in said body portion between said impression wheels and having characters relevant to the sales, said impression wheels and said plate being adapted to make a record on the sales slips pressed against them

of the quantity of merchandise sold, the total charge therefor and such other data as said plate may carry, and said impression wheels being keyed on said shaft and slideable to position thereon and therefrom.

3. A computing sales device as claimed in claim 1, in which said shaft is tubular and in which said body portion has a stationary axle on which said tubular shaft is mounted 10 and which axle is removably secured at its inner end to said rigid back portion and thence extends through the open front end of said casing.

4. A computing sales device as claimed in 15 claim 2, in which the body portion has a longitudinal dove-tail groove to receive said impression plate.

5. A computing sales device as claimed in claim 1, in which said knob and price 20 wheel are removable and in which said price wheel has removably positioned therewith an impression price ring or wheel bearing a series of characters aligned with the characters on the price wheel and denoting a fraction of a cent and multiples thereof to be 25 impressed on the sales slips.

6. A computing sales device as claimed in claim 1, in which said body portion has inking rollers mounted therein in the path 30 of motion of said quantity and price impression wheels, said inking rollers being positioned in spaces left therefor at the ends of said platen.

7. A computing sales device as claimed 35 in claim 1, in which said platen is pivoted at one end of said body portion and in which means are provided on said body portion and platen for squeezing the same together and against the sales slips interposed between them.

8. A manually operative computing sales device, comprising a body portion and a platen between which sales slips may be pressed to receive thereon the record of a sale, 45 said body portion comprising an elongated casing having a rigid back portion and being open at its outer or forward end and having a rotary shaft with means thereon for rotating it and associated with a set of numerals to guide the operator in rotating said shaft and which numerals are indicative of the quantities of merchandise sold, said shaft being insertible and removable through the open outer end of said casing, 50 an impression wheel mounted on said shaft and having thereon in relief a series of numerals corresponding with the aforesaid guide numerals and also indicative of the quantities of merchandise sold, and an impression wheel mounted on said shaft and

bearing in relief impression characters denoting the total price to be charged for the units represented by the corresponding numerals in said guide set and on said quantity impression wheel, said impression 65 wheels being adapted to make a record on the sales slips pressed against them of the quantity of merchandise sold and the total charge therefor, and said impression wheels being keyed on said shaft and slideable to 70 position thereon and therefrom.

9. A manually operative computing sales device, comprising a body portion and a platen between which sales slips may be pressed to receive thereon the record of a 75 sale, said body portion comprising an elongated casing having a rigid back portion and being open at its outer or forward end and having a rotary shaft with means thereon for rotating it and associated with a set 80 of numerals to guide the operator in rotating said shaft and which numerals are indicative of the quantities of merchandise sold, said shaft being insertible and removable through the open outer end of said casing, an impression wheel mounted on said shaft and having thereon in relief a series 85 of numerals corresponding with the aforesaid guide numerals and also indicative of the quantities of merchandise sold, an impression wheel mounted on said shaft and bearing in relief impression character denoting the total price to be charged for the units represented by the corresponding numerals in said guide set and on said 90 quantity impression wheel, and a stationary plate mounted in said body portion between said impression wheels and having characters relevant to the sales, said impression wheels and said plate being adapted to make 95 a record on the sales slips pressed against them of the quantity of merchandise sold, the total charge therefor and such other data as said plate may carry, said stationary plate representing the bottom of said casing and having the lower edges of the sides 100 of the casing secured to it.

10. A computing sales device as claimed in claim 1, in which the characters on said impression wheels are reversely disposed 110 with relation to the numerals on said knob, so that as the numerals on the knob are respectively turned to a definite exposed position, the cooperating numerals on the impression wheels will be turned to their 115 imprinting position.

Signed at New York city, in the county of New York and State of New York, this 17th day of December A. D. 1923.

CHARLES S. BATDORF.
